UNITED STATES PATENT OFFICE.

STEPHEN T. LESTER, OF EAST BAKERSFIELD, CALIFORNIA.

CONNECTING DEVICE.

Application filed March 14, 1923. Serial No. 624,991.

To all whom it may concern:

Be it known that I, STEPHEN T. LESTER, a citizen of the United States, residing at East Bakersfield, in the county of Kern and State 5 of California, have invented a new and useful Connecting Device, of which the following is a specification.

This invention relates to a connecting device for making a connection between two 10 devices or members, and particularly refers to a connecting device which may be quickly applied in case of an emergency for bringing an oil well into control.

In bringing in oil wells it sometimes happens that the well catches on fire or that the 15 oil commences to flow violently from the well in the form of a gusher and to seal the well and control the flow of gas or oil therefrom is impossible by the ordinary means.

20 An object of this invention is to provide a device which may be readily engaged with the well casing for sealing or temporarily shutting off the flow of oil or gas which device may be connected to suitable pipe lines 25 for withdrawing oil or gas from the well without the necessity of first removing the sealing means.

Another object of this invention is to provide an emergency device for controlling 30 oil wells which may be coupled with the well casing by directly forcing the device on to the end of the casing.

Another object of this invention is to provide a device for controlling oil wells which 35 may be forcibly engaged with the well casing and which may thereafter be connected to a pipe line and which device is provided with valve controlling means for sealing the oil well prior to the connection of the pipe 40 line, but which valve control means may be operated to permit the flow of gas or oil through the pipe line without removing the emergency device.

Another object of this invention is to provide 45 an emergency well controlling device with upwardly directed slips which may be forced in engagement with a well casing and which are slotted to permit an adjustment of the slips to fit the diameter of the well 50 casing and which slips are mounted on a tapered portion of a pipe connection so that after applying the device to a well casing a movement of the tapered portion of the pipe connection may effect a wedging of the slips 55 against the well casing to further insure the

sealing of the casing and gripping of the device to the well casing.

Various other objects and advantages of this invention will be apparent from the following description of the accompanying 60 drawings which illustrate a preferred embodiment of the invention in which—

Figure 1 is a vertical elevation of this embodiment of the invention.

Fig. 2 is a vertical section of Fig. 1 with 65 the pipe connection broken away to contract the view and with the device inserted into the well casing.

Fig. 3 is a section on the line 3—3 of 70 Fig. 2.

Figs. 4 to 6 inclusive illustrate a second embodiment of the invention, in which

Fig. 4 is a vertical elevation of this invention sectioned to disclose the slip engagement with the well casing. 75

Fig. 5 is an elevation of the slip member.

Fig. 6 is a plan view of Fig. 5.

In the drawings 1 generally indicates a well casing such as commonly extends from the well pit. 2 indicates a pipe section 80 which terminates in a threaded tapered portion 3 which is of less diameter at the end of the pipe connection. The pipe connection 2 is provided with a valve 4 for holding oil or gas and the upper end is formed with 85 threads 5 to which a pipe line (not shown) may be connected. 6 indicates a slip member which is tubular in form and provided on its outer vertical cylindrical surface with upwardly directed circular teeth 7, the peaks 90 of which teeth are directed sufficiently in an upward direction so that the slips may be readily forced inside a casing or pipe but will grip the pipe and prevent the removal therefrom. The inner bore 8 of the slip member 6 is conically threaded to fit the threads on the tapered portion 3 of the pipe connection 2 and the slip member 6 is formed with a plurality of slits 9 which extend 95 vertically from the bottom of the member upwardly but preferably are not extended to the upper end of the member so as to maintain the member in integral form.

Preferably slits 10 are also provided in staggered relation to the slits 9, said slits 10 extending from the upper end of the member substantially vertically downward. Said slits 10 terminate considerable distance from the lower end of the slip member so that the pipe connection 2 may prevent com- 110

munication with the interior of the well casing by overlapping the slits 10 while leaving considerable overlapping ends for later adjustment of the device. 11 indicates a plurality of bumper arms connected to the bottom of the slip member 6 which are joined together in the form of a conical bumper or guide for the device. 12 indicates a quantity of suitable pliant material which 10 covers the slip teeth 7. Various materials may be used but rubber is preferred for this purpose. Said materials aid in sealing or packing the slip member 6 into the well casing 1.

15 When applying the device to a well casing the slips 6 are screwed onto the tapered portion 3 of the member 2 until said portion 2 extends from the lower end of the slits 10. The valve 4 is opened and the device is forced into the well casing to engage the slip member 6 therewith. The arms 11 aid in guiding the member inside the casing and the slits 9 and 10 permit a contracting of the slip member so that the same 20 may be readily forced into the casing. Since the slip member 6 does not properly seal the pipe connection 2 to the casing 1, the pipe connection 2 may be screwed into the slip member and the tapering of the portion 3 will expand the member 6 forcing the teeth into the casing and effectively sealing the casing to the slip member. A pipe line may then be connected to the threads 5 and the oil or gas withdrawn from the well without 25 the necessity of removing the slip member 6 therefrom.

The well may be held from flowing the necessary time to secure pipe connections for carrying away the oil or gas which may 30 be coupled to the device without removing the same and while the flow of oil or gas is fully shut off. The slits 9 and 10 in the bottom and top of the slip member 6 adapt the member to fit readily into the well casing by contacting said member, which may 35 be later expanded through screwing the pipe connection 2 downwardly through the threads of the member 6.

Referring to Figs. 4, 5 and 6 of the drawings the invention is illustrated in a modified form in which the construction and operation of the parts is somewhat reversed to permit the emergency device to engage the exterior of the casing.

40 In the drawings 1^a generally indicates a well casing. 2^a indicates a pipe connection which terminates in an internally threaded tapered portion 3^a which is of greater diameter at the lower end of the pipe connection. The pipe connection 2^a is provided with a valve 4^a for holding oil or gas and the upper end is formed with threads 5^a to which a pipe line (not shown) may be connected. 6^a indicates a slip member which 45 is tubular in form and provided on its inner

vertical cylindrical surface with upwardly directed circular teeth 7^a, the peaks of which teeth are directed sufficiently in an upward direction so that the slips may be readily forced over the exterior of a well casing 70 or pipe, but will grip the pipe and prevent the removal therefrom. The exterior surface 8^a of the slip member 6^a is tapered and threaded to fit the threads on the tapered portion 3^a of the pipe connection 2^a and 75 the slip member 6^a is formed with a plurality of slits 9^a which extend vertically from below the lower end of the circular teeth 7^a upwardly but preferably not extended to the upper end of the slip member 80 6^a so as to maintain said member 6^a in integral form. Preferably slits 10^a are also provided in staggered relation to the slits 9^a, said slits 10^a extending from the upper end of the slip member substantially vertically downward.

Said slits 10^a terminate a considerable distance from the lower end of the threaded portion 8^a of the slip member 6^a, so that the pipe connection 2^a will prevent communication between the atmosphere and the interior of the well casing by overlapping such slits 10^a while said pipe connection 2^a is still in position to permit further adjustment of the device. Below the threaded portion 8^a of the slip member 6^a said member is expanded in the form of a bell as indicated at 11^a, which bell formation thereof acts as a guide when applying the device to the well casing. 12^a indicates a quantity 100 of suitable pliant material which covers the slip teeth 7^a. Rubber is to be preferred for said material which aids in sealing or packing the slip member 6^a into the well casing 1^a.

105 When applying the device to a well casing the slip member 6^a is screwed on to the tapered portion 3^a of the member 2^a until such tapered portion 3^a extends over the lower end of the slits 10^a. The valve 4^a is 110 opened and the device is forced on to the well casing 1^a to engage the slip member 6^a therewith. The bell formation 11^a aids in guiding said member over the casing 1^a and the slits 9^a and 10^a permit an expansion of the slip member so that the same may be easily 115 forced on to the casing. Since the slip member 6^a will not then normally seal the pipe connection 2^a to the casing 1^a the pipe connection 2^a may be screwed over the slip member and the tapering of the portion 3^a will contract the member 6^a forcing the teeth into the casing 1^a and effectively sealing the casing to the slip member. The valve 4^a 120 may then be closed and the pipe connected to the threads 5^a and the valve 4^a opened and oil or gas withdrawn from the well without the necessity of removing the emergency device therefrom.

125 While I have described the invention as it 100

- is applied to an emergency well controlling device, the invention may have other uses and it is intended to cover the invention irrespective of the use to which it is put.
- 5 Various changes may be made in the details of construction of the device herein illustrated which device is illustrated as a practical example of the invention. The invention is not limited to the example 10 shown but may be modified in various ways without departing from the spirit of the invention. This invention is of the scope set forth in the following claims.
- I claim:
- 15 1. In a device of the class described, the combination with a pipe section, terminating in a tapered portion, of a member adapted to fit over said tapered portion and having upwardly directed slips disposed on its outer 20 surface, said member being slit from the lower end upwardly to provide for adjustment of the member in engaging the well casing.
- 25 2. In a device of the class described, the combination with a pipe section terminating in a tapered portion, of a member having a screw engagement with said tapered portion and having upwardly directed slips disposed 30 on its outer vertical surface, said member being slit at the top and bottom to permit adjustment thereof in engaging the well casing.
3. In a device of the class described, the combination with a pipe section and valve control means for said pipe section, of slips 35 mounted by said pipe section slit to contract in engaging a well casing.
4. In an emergency well controlling device, the combination with a pipe section having a lower threaded tapered portion, of 40 valve control means for said pipe section, and a slip member threaded on said lower threaded portion of said pipe section, said member being slit to permit adjustment thereof in engaging a well casing, and bumper 45 arms joined to said slip member for guiding the device in engagement with said well casing.
5. In a device of the class described, the combination with a pipe section terminating 50 in a tapered portion and valve control means for said pipe section, of a slip member threaded on said tapered portion providing upwardly directed wedging teeth, said slip member being slit at the upper and lower 55 ends to permit adjustment thereof, bumper arms for guiding said slip member in engagement with a well casing, and pliant material surrounding said upwardly directed teeth for packing the same in the well casing. 60

Signed at Los Angeles, California, this 9th day of March, 1923.

STEPHEN T. LESTER.
